CLAIM

The ornamental design for an automobile headlight, as shown and described.

DESCRIPTION

FIG. 1 is a perspective view of an automobile headlight; FIG. 2 is a front view thereof;

FIG. 3 is a side view thereof;

FIG. 4 is a top view thereof; and,

FIG. 5 is a bottom view thereof.

Any broken lines are included to show environmental structure and form no part of the claimed design.

The drawings and descriptions disclose the right side embodiment. The claim is also for a mirror image left side embodiment.

1 Claim, 5 Drawing Sheets(56)
